(57) **CLAIM**

The ornamental design for a zipper tooth, as shown and described.

DESCRIPTION

FIG. 1 is a front view of a zipper tooth according to a first embodiment of the present application;

FIG. 2 is a rear view of the zipper tooth according to the first embodiment of the present application;

FIG. 3 is a left view of the zipper tooth according to the first embodiment of the present application;

FIG. 4 is a right view of the zipper tooth according to the first embodiment of the present application;

FIG. 5 is a top view of the zipper tooth according to the first embodiment of the present application;

FIG. 6 is a bottom view of the zipper tooth according to the first embodiment of the present application;

FIG. 7 is a perspective view of the zipper tooth according to the first embodiment of the present application;

FIG. 8 is a front view of a zipper tooth according to a second embodiment of the present application;

FIG. 9 is a rear view of the zipper tooth according to the second embodiment of the present application;

FIG. 10 is a left view of the zipper tooth according to the second embodiment of the present application;

FIG. 11 is a right view of the zipper tooth according to the second embodiment of the present application;

FIG. 12 is a top view of the zipper tooth according to the second embodiment of the present application, with a lined portion indicating color contrast;

FIG. 13 is a bottom view of the zipper tooth according to the second embodiment of the present application; and,

FIG. 14 is a perspective view of the zipper tooth according to the second embodiment of the present application, with a lined portion indicating color contrast.

1 Claim, 14 Drawing Sheets
